WELL TOOL

Jopling P. Smith, Houston, Tex., assignor, by
mesne assignments, to John H. McCarvell

Application June 29, 1945, Serial No. 602,183

3 Claims. (CL. 166—12)

1

This invention relates to new and useful improvements in a well tool, and in particular in a tool which may be lowered into a well to a desired position and desirably set or positioned therein, and thereafter released for resetting and/or removal from the well. The invention is of particular utility for, and is disclosed herein as comprising an expansible packer to form a pack-off between concentric tubular strings in a well.

The primary object of the invention is to provide a well tool that may be run into a well upon an operating string which can be manipulated at the mouth of the well to set and thereafter release the tool so that operations within the well, conditioning of the well or production thereof, can be accomplished.

Another object is to provide a tool of the class described in which manipulative rotation of the operating string is unidirectional. Threads which are adapted to become disconnected when rotating the operating string are usually right hand threads and it is contemplated that the tool of the present invention shall be so constructed that right hand rotation of the operating string can be utilized for operating purposes, it being understood of course, that the device may be so constructed that left hand rotation may be utilized to serve any specific purpose.

A further object is to provide a device which is simple and inexpensive to construct and maintain, and one in which the component parts are few in number and are of rugged construction.

It is also an object to provide a tool having telescopic elements including a by-pass assembly so that resistance to movement of the device within a well from the fluids therein is minimized.

A still further object is to provide a tool including a slip or anchor assembly and means for setting or releasing such assembly with facility and in a manner to obviate hanging up of the tool within the well.

A more specific object is to provide a tool having a drag or spring cage assembly with which selective engagement may be had to effect desired interconnection or disconnection of parts of the device so that setting or releasing of the tool may be effected.

The foregoing objects are primary objects which, together with other objects and advantages of the invention, will be more fully apparent from the following description considered in connection with the accompanying drawings in which:

Figs. 1 and 2 are successive elevational views

2
partly in section of one embodiment of the invention showing the relative position of parts when the device is being lowered to a predetermined operating position within a well;

5 Fig. 3 is an elevational view in section of a modified form of the lower portion of the device shown in Fig. 2;

Figs. 4 and 5 are similar to Figs. 1 and 2, but are sectional elevations showing the tool set 10 within a well casing;

15 Fig. 6 is an elevational view of the lower portion of the device showing the driving connection between the operating string and the remainder of the device whereby the parts of the device are interconnected by rotation of the string;

Figs. 7 and 8 are similar to Figs. 1 and 2, but show a modified form of the interconnecting and releasing portion of the device;

20 Figs. 9 and 10 show the relative position of parts of the device of Figs. 7 and 8 when the device is set within a well casing.

Like references are used to identify the respective like parts of the different embodiments shown in the drawings. Referring generally to the drawings the device of the invention includes a tubing or operating string 1 comprising a bypass section 2 interposed between the coupling 3 and the lift collar 4. Extending downwardly 25 from said collar is a section 5 having actuating pins 6 below which the string extends downwardly at 7 to such level as is deemed desirable or necessary for the purpose for which the tool is used.

30 A packer and slip assembly 10 surrounds the string 1, and the lower portion of this assembly is surrounded by a spring or friction cage assembly 30 which cooperates with a latch collar 40 so that operation of the tool may be effected by desired manipulation of the string 1 at the mouth 35 of the well.

The upper end of the assembly 10 comprises a head 11 having an internal shoulder 12 engageable by the lift collar 4 to support the assembly 40 upon the string when going into or coming out of the well. The bypass section 2 passes outwardly from within the head 11 and has openings 13 therein so that fluids may enter into or exit from the string through such openings while the device is being moved within a well. When the device is set within a well, as will more fully appear, and the string 1 is lowered until the coupling 3 lies proximate the upper end of the head 11, the bypass openings 13 are within the 45 assembly 30 as best seen in Fig. 4 and hence are 50 55

closed except for the passage through the string 1. Leakage through the head 11 about the string is prevented by means of packing 14 in the head.

The packer sleeve 15 is secured to the head 11 and has packing rings 16 thereon. This sleeve has a flange 17 at its lower end to cooperate with a complementary flange 18 on the upper end of the expander 19 which has tapered surfaces 20 at its lower end for engagement with the inner surfaces 21 of a plurality of slips 22 having casing engaging teeth 23. The lower ends of these slips are attached to the upper end of slip collar 24 by suitable means such as the T-slot connection 25 whereby the slips may move radially during the setting or releasing operation of the tool.

It seems apparent that when the collar 24 is permitted to rise relative to the expander 19, the slips 22 will ride upon the surfaces 20, and hence the slips will move outwardly to the position indicated in Figs. 5 and 10. The assembly 10, whether such assembly comprise a packer as shown or other device to be set in a well, may thus be anchored and the operating string 1 may be lowered therein until the collar 3 engages the upper end of the head 11. Obviously further lowering of the string 1 moves the head 11 and its associated sleeve 15 downwardly whereby the rings 16 are expanded as indicated in Figs. 4 and 9 and hence form sealing engagement with the surrounding casing 26.

Reference is now made to the construction whereby the latch collar 40 and the slip collar 24 may be interconnected or released by unidirectional rotation of the string 1 at the mouth of the well. Inasmuch as the operating string such as that shown at 1 comprises a plurality of sections of tubing interconnected by means of right hand threads, as above indicated, it is desirable that only right hand rotation of the operating string be effected and the construction as shown provides for such rotation both for actuating the tool, for setting when the desired level is reached, and for releasing the tool when it is to be withdrawn from the well or to be reset at a different level.

The spring or friction cage assembly 30 comprises a plurality of bow springs 31 secured in a suitable manner upon the cage 32 and extending longitudinally thereof. This assembly is floatably mounted upon the collar 24, its limit of movement being determined by flanges 27 and 28. By virtue of its contact with the surrounding casing the assembly assumes lagging position as the tool is moved within a well bore. The upper end of the cage has an ear 33 engageable with a complementary ear 34 on the collar 24 when the latter is rotated in a clockwise or right hand direction as viewed from above. Also the lower end of the cage 32 has an ear 35 engageable by the ear 36 on the latch collar 40 when the latch collar is rotated in a clockwise direction relative to the spring cage.

The latch collar 40 has one or more slots 41 therein each including a horizontal portion 42 and a vertical portion 43 which receives the pins 44 projecting radially from the member 24 near its lower end. The latch collar 40 also has internal recesses 45 which receive the drive pins 6 when the pins 44 are in the portion 42 of the slot 41. While a generally L-shaped slot is provided by the structure just described it is to be understood that any suitable means may be provided for interconnecting and releasing the component parts of the assembly. This is illustrated in the

further description of additional embodiments of the invention.

The operation of the device thus far described is believed apparent from the description. By way of reiteration it will be assumed that the parts of the device are initially in the relative positions shown in Figs. 1 and 2. As the device is lowered within a well the packer rings 16 move in close contiguity with the surrounding casing. This does not, however, impede movement of the device inasmuch as fluids within the casing may move upwardly within the string 1 and thence outwardly through the openings 13. In this manner the fluids are effectively by-passed.

When the device has reached the level at which the slips 22 are to be set, whether the slips are to be used for expanding a packer within the well or for other purposes, the string 1 is rotated in a clockwise direction whereby the collar 40 is driven by pins 6 until the pins 44 enter the lower ends of the vertical portions 43 of the slots 41. The string 1 is then moved downwardly and first closes the by-pass through the openings 13 after which the collar 3 engages the upper end of the head 11. Continued movement of the string causes the mandrel 19 to move downwardly relative to the slips 22 which together with the collar 24 remain stationary due to resistance of the cage 30 with the surrounding casing 26. During this movement the pins 44 move upwardly within the portion 43 of the slots 41. At the same time the rings 16 are expanded and thus the tool assumes the set position shown in Figs. 4 and 5.

If the device is to be released for resetting at a different level or for removal from the well, the string 1 is thereafter lifted and the lift collar 4 engages the shoulder 12 on the head 11 whereby further lifting unseats the packer. Thereafter the expander 19 is lifted so that the slips 22 are released. At the same time of course the pins 6 have risen to a position of engagement with the projections 46. Likewise, the collar 40 has been lifted with the string until the pins 44 are opposite the portion 42 of the L-shaped slot 41. Any additional lifting of the string 1 moves the string and associated elements upwardly relative to the spring or friction cage 30 whereby the ears 33 and 34 are separated while the ears 35 and 36 are moved into engageable positions.

The operating string 1 is then rotated in a clockwise direction whereby the pins 6 engage the projections 46 at the lower end of the slip collar 24 and the entire assembly 10 is rotated by the string 1. Initiation of such rotation also causes the pins 44 to enter the portion 42 of the slot 41, the collar 40 being restrained from rotation by interengagement of the ears 35 and 36 on the spring cage and the collar respectively. In this manner the device is released from its set position as shown in Figs. 4 and 5 and returned to its initial position as shown in Figs. 1 and 2 so that it may be reset in a different level or withdrawn from the well for reuse.

The operation of the device as shown in Fig. 3 is the same as that just described in connection with Figs. 1 and 2. In this modified construction, however, the latch collar 40' is provided with inwardly extending pins 44' which enter inverted L-shaped slots 41' in the lower end of the slip collar 24.

In the embodiments shown in Figs. 7 to 10 inclusive the modified latch collar 40'' is constructed to fit slidably upon the operating string below the driving pins 6. This collar has outwardly extending pins 50 which are adapted to

enter slots 51 formed in the lower end of the slip collar 24. The upper end of the collar 40" is also provided with recesses forming surfaces 52 adapted to be engaged by the drive pins 6 whereby the collar may be forced to rotate with the operating string. Thereabove the slip collar 24 is likewise provided with recesses forming surfaces 53 engageable by the drive pins 6 in a manner to be explained. It is also to be noted that the pins 50 extend outwardly beyond the periphery of the lower end of the collar 24 so that such pins are likewise engageable with the ear 35 at the lower end of the spring cage 30.

In the operation of this embodiment the parts are in the relative positions shown in Figs. 7 and 8 when the device is to be lowered within a well, the pins 50 being engaged within the slots 51 at the lower end of the collar 24. When the device is to be set the operating string 1 is rotated in a clockwise direction whereby the collar 40" is rotated and the pins 50 are withdrawn from within the slots 51. Thereafter lowering of the operating string moves the parts to the relative positions shown in Fig. 10 whereby the slips 22 are set and the packer rings 16 are expanded within the casing 25 as shown in Fig. 9.

When the device is to be released for resetting or for removal from the well the operating string is lifted until the driving pins 6 move to a position to engage the surfaces 53 at the lower end of the slip collar 24. At the same time the latch collar 40" is lifted until the pins 50 engage the ears 35 at the lower end of the spring cage whereby the latch collar is restrained from rotation. Continued rotation of the operating string thus causes the slip collar 24 to move relative to the pins 50 so that such pins again become latched within the slots 51 and the device is again interconnected in inoperative position.

Broadly the invention comprehends a well tool which may be lowered into a well upon an operating string, which may be manipulated at the mouth of the well to set and to thereafter release the tool by manipulation of the string, any rotation of the string in such operation being unidirectional.

What is claimed is:

1. An oil well tool comprising, an operating string having a shoulder thereon, a packer and slip assembly surrounding the string and having a complementary internal shoulder so that the assembly is normally suspended on the string, said assembly including a slip collar extending downwardly about the string, a friction cage slidably surrounding said slip collar, a latch collar surrounding the operating string below the friction cage, a pin and slot connection between the

slip and latch collars, there being spaced opposed recesses on said collars, and actuating pins on the string normally engaged within the recesses in the latch collar to hold the slip collar against upward movement while the tool is lowered into a well bore.

2. An oil well tool comprising, an operating string having a shoulder thereon, a packer and slip assembly surrounding the string and having a complementary internal shoulder so that the assembly is normally suspended on the string, said assembly including a slip collar extending downwardly about the string, a friction cage slidably surrounding said slip collar, a latch collar surrounding said slip collar, ears on said collars above and below said friction cage, complementary ears on the friction cage, a pin and slot connection between the slip and latch collars, there being spaced opposed recesses on said collars, and actuating pins on the string normally engaged within the recesses in the latch collar to hold the slip collar against upward movement while the tool is being lowered.

3. An oil well tool comprising, an operating string having a shoulder thereon, a packer and slip assembly surrounding the string and having a complementary internal shoulder so that the assembly is normally suspended on the string, said assembly including a slip collar extending downwardly about the string, a friction cage slidably surrounding said slip collar, an outwardly extending pin on said slip collar, a latch collar surrounding the slip collar and having an L-slot into which said pin projects, there being vertically spaced recesses in said collars, actuating pins on said string normally engaged within the recesses in the latch collar to hold the slip collar against upward movement while the tool is lowered into a well bore, said friction cage slidably surrounding the slip collar above the latch collar and having ears on the ends thereof, and complementary opposed ears on the slip and latch collars for selective interengagement with the ears on the friction cage so that the pin can be released from the latching portion of the L-slot and thereafter reengaged by unidirectional rotation of the operating string.
